UNITED STATES PATENT OFFICE

CHARLES DE VRIENDT, OF PARIS, FRANCE, ASSIGNOR TO WESTERN ELECTRIC COMPANY, INCORPORATED, OF NEW YORK, N. Y., A CORPORATION OF NEW YORK

TELEPHONE EXCHANGE SYSTEM

Application filed September 1, 1931, Serial No. 560,543, and in France November 21, 1930.

This invention relates to telephone systems and more particularly to telephone systems in which connections are established from a manual office to offices equipped with 5 dial switching apparatus by switching apparatus under the control of operators at the manual office. There are, in general, two different methods which may be employed by operators to control the setting of automatic 10 switching apparatus, the usual dial such as is used at subscribers' substations and a keyset comprising a key for each of the numerical digits 0 to 9 inclusive. It may be desirable in some cases to enable operators to employ 15 either method of impulsing and it is therefore the object of the present invention to provide facilities for enabling operators to establish connections by dialing the designations of wanted lines or by setting up such 20 designations on a keyset.

In accordance with the present invention, the operator has access to a group of outgoing trunks, each trunk being provided with discriminating means responsive to the operation or non-operation of a dialing key in the operator's cord circuit which determines whether the trunk circuit shall be associated with a common register sender which is equipped to respond to impulses from the operator's position dial, or whether the trunk circuit shall be associated with a common sender which is equipped to respond to control from the operator's position keyset. While the invention has been disclosed as 35 equipped with two different types of senders, it will be apparent to those skilled in the art that a single group of senders might be employed, arranged to receive registrations in accordance with the discrimination set up in the trunk circuit through the operation of a dial or of a keyset.

The invention is particularly, although not exclusively, applicable to private branch exchanges connected to a network employing 45 automatic switching apparatus, since it provides means whereby if a connection is extended over a trunk to the main exchange from an operator's position of the private branch exchange, the controlling impulses may be transmitted from a keyset, whereas,

if a connection is to be extended from a subscriber's station in the private branch exchange, the impulses may be transmitted from a dial over the same trunk, there being no action necessary on the part of the operator or subscriber other than the usual sending operation since either a dial or keyset may be used indiscriminately at the outgoing end of the trunk circuit.

Another aspect of the invention relates to 60 an improved method of setting up the registering mechanism of a sender by means of impulses transmitted from a keyset, the arrangement being such that impulses of either direct or alternating current or a combination 65 of both may be transmitted from the keyset over either or both of the talking conductors of the operator's cord circuit and the talking conductors of the outgoing trunk circuit according to the digits transmitted, 70 whereby great flexibility may be provided and the impulses may be transmitted over long lines in order to set up recording apparatus at the distant end of the trunk.

Although the invention is concerned primarily with the discrimination set up in the outgoing trunk circuits in accordance with the impulsing method elected by the operator and with the improved method of key pulsing, it has been deemed best to disclose 80 in considerable detail the apparatus employed for cooperation with the operator's equipment in establishing connections by the two impulsing methods.

The invention will be more clearly understood from the following detailed description which relates to one embodiment of the invention selected for the purpose of illustration and disclosed in the accompanying drawings, in which:

Fig. 1 shows a portion of an operator's cord circuit, dial and keyset and an outgoing trunk circuit;

Figs. 2 and 3 taken together show a line 95 finder having access to the trunk circuit of Fig. 1 and a district selector for extending connections under the control of the operator's keyset;

Figs. 4, 5, 8, 9, 10, 14, 15 and 20 taken together show a register sender for controlling 100

selector switches and arranged to register impulses from the operator's keyset. Fig. 4 shows a trunk finder for connecting the sender with the line finder link. Figs. 5 and 9 show control sequence switches of the sender. Figs. 10, 15 and 20 show relay registers for recording impulses from the operator's keyset. Fig. 8 shows the counting relays and Fig. 14 shows secondary code digit registers and translator for registering and translating the code digits registered on the code digit registers of Figs. 10 and 15;

Fig. 6 shows the circuit of a primary line finder having access to the trunk circuit of Fig. 1 for extending connections when dial impulses are transmitted from the operator's position;

Figs. 7 and 12 taken together show a line finder district selector link, Fig. 7 showing at the left the brushes of a secondary line finder having access to the primary line finder of Fig. 6, and at the right the brushes of a district selector, and Fig. 12 showing the control sequence switch of the link circuit and a sender selector switch;

Figs. 11, 13, 16, 17, 18 and 19 taken together show a register sender of the type responsive to impulses from a dial for registering line designations and controlling the setting of selector mechanism. Figs. 11 and 13 show control sequence switches of the sender, Fig. 16 shows sender timing and control circuits, Fig. 17 shows the translator circuit, Fig. 18 shows the counting relays and Fig. 19 shows the digit registers; and

Fig. 21 is a diagram illustrating how the several figures should be arranged to show the complete circuits of the invention.

40 Registration controlled by dial

In the following description only the operation of such circuits as are particularly necessary to the understanding of the invention will be discussed in detail. It will be first assumed that the operator elects to use her position dial 100 and therefore inserts the cord circuit plug 101 into the outgoing trunk jack 102 with the dialing key 103 in normal position. With the cord circuit thus connected to the outgoing trunk circuit, a circuit is established from battery, winding of relay 104, left back contact of relay 105, ring contacts of jack 102 and plug 101, right normal contacts of key 103, contacts of dial 100, left normal contacts of key 103, tip contacts of plug 101 and jack 102, winding of relay 106 to ground at the right back contact of relay 105. Relay 106 does not operate in this circuit as it is marginally wound but relay 104 operates, closes an obvious circuit for group relay 107 and places battery potential on the test terminal 601 appearing in the banks of line finders such as 600 to mark the trunk 110 as calling.

65 Relay 107 in turn establishes parallel cir-

cuits for start relays 602, 603, 604 of all primary line finders such as 600 having access to the trunk 110 and these relays in turn close circuits for the motor magnets of such line finders. The circuit of magnet 605 of the line finder 600 may be traced from ground through the winding of relay 606, outer right contacts of relay 602, upper normal contacts of jack 607, winding of magnet 605, back contact of relay 608, back contact of relay 609 to battery. Magnet 605, in the well known manner, advances the brushes of the line finder 600 until test brush 610 engages terminal 601, when battery potential on terminal 601 is extended through the left winding of relay 609 to ground at the lower normal contacts of jack 607. Relay 609 thereupon operates, opening the circuit of magnet 605, placing battery potential on the test terminal 701 in the banks of secondary line finders such as 700, and closing a circuit from battery at the front contact of relay 609, right winding of relay 608, winding of relay 611, winding of relay 612 to ground. Relay 608 operates in this circuit, opening at its right back contact another point in the circuit of magnet 605 and at its left contact connecting the low resistance right winding of relay 609 to ground in parallel with the left winding of relay 609 to render the trunk circuit 110 unselectable to other line finders. Relay 107 being now shunted by a low resistance path releases, thereby opening the circuit of relays 602, 603 and 604 to stop all other hunting line finders.

Relay 611 upon operating closes an obvious circuit for group relay 628 which in turn closes circuits for the start relays such as 613 and 614 of all secondary line finders such as 700 which have access to the primary line finder 600. Relay 614 upon operating closes a circuit from ground, winding of relay 615, outer right contacts of relay 614, conductor 616, lower normal contacts of jack 1201, left contacts of cam 1202, conductor 1203, inner right back contact of relay 702, right winding of relay 703 to battery. Relay 703 operates in this circuit and closes a circuit for the magnet 704 extending from battery, winding of magnet 704, conductor 705, upper left contact of cam 1204, upper left contact of cam 1205, conductor 706, right front contact of relay 708, right back contact of relay 707, conductor 708, lower left contact of cam 1206, to ground at the lower left contact of cam 1207. Relays 613 and 614 close similar driving circuits for other secondary line finders having access to the primary line finder 600.

When the line finder 700 has advanced to the terminals of its bank connected to line finder 600, battery potential on terminal 701 is extended over brush 709, conductor 710, under normal contacts of jack 1201, conductor 1208, upper normal contacts of jack 1700,

- conductor 1701, left contacts of cam 1209, conductor 1210 to ground through the left winding of relay 707. Relay 707 operates opening the circuit of magnet 704. With relay 707 operated a circuit is established from brush 709 as traced through the lower left contact of cam 1209, thence over the upper right contact of this cam, conductor 1211, right winding of relay 707, left winding of relay 711, conductor 712, lower contacts of cam 1212, conductor 1213, front contacts of relay 707, conductor 708, lower left contact of cam 1206, to ground at the lower left contact of cam 1207. Relay 711 operates in this circuit closing a circuit extending from battery, winding of relay 702, conductor 713, upper contacts of cam 1214, conductor 1215, to ground at the contacts of relay 711. Relay 702 upon operating locks in a circuit through its winding, conductor 713, left contacts of cam 1214, conductor 1216, to ground at the outer left contacts of relay 702 and, at its inner right front contact opens the circuit of relay 703 which releases opening a second point in the circuit of magnet 704 and releasing relays 707 and 711. Relay 702 at its inner left front contact with relay 703 released now closes a circuit extending from battery, windings of relays 105 and 108 in parallel, conductor 625, terminal 617 and brush 618 of line finder 600, left winding of relay 608, terminal 714 and brush 715 of line finder 700, winding of relay 716, left back contact of relay 703 to ground at the inner left front contacts of relay 702.

Relays 105, 108 and 716 operate, relay 108 closing a shunt extending over its front contact, the left back contact of relay 109 around the winding of relay 106. Relay 105 upon operating opens the circuit of relay 104 which in turn opens the previously traced circuit for relay 609 which also releases. Relay 716 upon operating establishes a circuit from battery, winding of relay 717, conductor 718, lower left contact of cam 1217, upper right and lower left contacts of cam 1218, conductor 1219, left contact of relay 716, brush 719, terminal 720, brush 619, terminal 620, conductor 621, ring contacts of jack 102 and plug 101, right normal contacts of key 103, contacts of dial 100, left normal contacts of key 103, tip contacts of plug 101 and jack 102, front contact of relay 108, left back contact of relay 109, conductor 622, terminal 623 and brush 624, terminal 721 and brush 722, inner right front contact of relay 716, conductor 723, right contacts of cam 1220, conductor 1221, to ground through the winding of relay 724. Relays 717 and 724 operate in this circuit, relay 717 closing a circuit for advancing sequence switch 1200 into position 3. This circuit may be traced from battery, winding of the sequence switch magnet, upper contact of cam 1222, upper left contact of cam 1223, conductor 1224, front contact of relay 717, conductor 725, lower left contact of cam 1225 to ground at cam 1207. As soon as sequence switch 1200 leaves position 1½ the locking circuit of relay 702 is opened at cam 1214 and relay 702 releases and extends the holding circuit for relays 105, 108, 608 and 716 over the inner left normal contact of relay 702, conductor 726 to ground over the upper right contact of cam 1207.

With sequence switch 1200 in position 3, a circuit is established for the operating magnet 727 of the sender-finder 1250 which may be traced from battery, winding of magnet 727, conductor 728, the upper right contact of cam 1204, the lower left contact of cam 1205, back contact of relay 707, conductor 708, lower left contact of cam 1206, to ground at cam 1207. When the brushes of sender-finder 1250 are positioned upon the terminals of an idle register sender a circuit is established from battery, winding of relay 1600, conductor 1601, upper right and lower left contacts of cam 1101, conductor 1102, normal contacts of jack 1602, conductor 1603 to terminal 1226 of the sender-finder 1250 and in parallel from battery through resistance 1604, conductor 1605, lower contacts of cam 1301, conductor 1601 and thence as traced to terminal 1226, thence over brush 1227, conductor 1228, outer right back contact of relay 703, conductor 729, lower right and upper left contacts of cam 1209, conductor 1210 to ground through the left winding of relay 707. Relay 707 operates in this circuit locking from battery on brush 1227, over conductor 1228, back contact of relay 703, conductor 729, right contacts of cam 1209, conductor 1211, right winding of relay 707, left winding of relay 711, conductor 712, lower contacts of cam 1212, conductor 1213, front contact of relay 707, conductor 708, lower left contact of cam 1206 to ground at cam 1207. The potential on terminal 1226 is thereby diminished to mark the selected sender as busy to other sender-finders such as 1250.

Relay 711 closes a circuit for relay 702 extending from battery, winding of relay 702, conductor 713, upper contacts of cam 1214, conductor 1215 to ground at the contacts of relay 711, relay 702 locking over the left contacts of cam 1214, conductor 1216 to ground at the outer left contacts of relay 702, and closing a circuit for advancing sequence switch 1200 from position 3 into position 4. This circuit may be traced from battery, winding of magnet 1200, lower left and upper right contacts of cam 1229, conductor 1230 to ground at the outer left contacts of relay 702. As soon as the sequence switch leaves position 3 the holding circuit of relay 702 is opened and relay 702 releases.

At the sender, relay 1600 operates in the circuit above traced therethrough and closes a circuit for relay 1606 extending over conductors 1607 and 1103, right contacts of cam 1301

1104, conductor 1105, left front contact of relay 1600, conductor 1608, upper left contact of cam 1106 to ground at cam 1107. Relay 1606 in turn closes a circuit for relay 1609 over conductor 1610 to ground at the front contact of relay 1606, a circuit over conductor 1610, right contacts of cam 1108, conductor 1109 to battery through the winding of relay 1611, and a circuit from ground over conductor 1610, the upper contacts of cam 1108, conductor 1143 to battery through the winding of relay 1800. Relay 1800 advances sequence switch 1100 from position 1 into position 2 over a circuit extending from battery, winding of sequence switch magnet 1100, contact of cam 1110, lower right contact of cam 1111, conductor 1112 to ground at the outer right front contact of relay 1800. Relay 1611 closes a circuit for relay 1612 extending from battery through the winding of this relay, outer right back contact of relay 1613, outer right normal contacts of relay 1614, contacts of relay 1611 to ground at the normal contacts of jack 1602. Relay 1612 in turn closes a circuit from battery, winding of relay 1615, left front contact of relay 1612, conductor 1616, upper right contact of cam 1113 to ground at cam 1107.

With relay 1615 operated a circuit is established from battery, winding of magnet 1617 of the timing switch 1620, normal contact of jack 1618, inner right back contact of relay 1614 to ground at the left front contact of relay 1615. As soon as sequence switch 1100 leaves position 1, relay 1800 releases and as soon as this sequence switch passes beyond position 1½ relay 1606 releases followed by the release of relays 1609, 1611, 1612 and 1615. Relay 1615 upon releasing opens the circuit of magnet 1617. If the pulsing circuit has at this time been extended to the windings of pulsing relay 1619 from battery, right winding of relay 1619, right winding of induction coil 1621, inner left back contact of relay 1613, conductor 1622, terminal 1231 and brush 1232 of sender-finder 1250, lower contacts of cam 1218, conductor 1219, left contact of relay 716, thence as traced through the pulsing contacts of the operator's dial returning over the inner right front contact of relay 716, conductor 723, lower contacts of cam 1220, brush 1233 and terminal 1234, conductor 1235, middle winding of coil 1621 to ground through the left winding of relay 1619 and relay 1619 is operated, sequence switch 1100 advances from position 2 into position 3½. The circuit of the sequence switch magnet may be traced from battery through the sequence switch magnet winding, contact of cam 1110, upper left contact of cam 1111, conductor 1114 to ground at the front contact of relay 1619. If, however, relay 1619 has not operated, then when relay 1615 releases as previously described, sequence switch 1100 is advanced from position 2 into

position 13 over a circuit extending through the sequence switch magnet winding, contact of cam 1110, lower left contact of cam 1111, conductor 1115, right back contact of relay 1615, back contact of relay 1623 to ground. 70 In position 13 the sender is released. If relay 1619 operates in the meantime, relay 1611 operates over conductor 1109, lower contacts of cam 1108, conductor 1114 to ground at the front contact of relay 1619 and closes the 75 previously traced circuit for relay 1612. Relay 1612 in turn closes the previously traced circuit for relay 1615 which now locks over the left front contact of relay 1612, the right front contact of relay 1615 to ground at the 80 back contact of relay 1623 and opens the circuit of the magnet of sequence switch 1110 to arrest the sequence switch in position 3½. With sequence switch 1100 in position 3½ a dialing tone is transmitted to the operator's 85 position over the circuit previously traced through the windings of coil 1621, tone current being induced into the middle and right windings of coil 1621 from battery, left winding of coil 1621, conductor 1630, the lower right and upper left contacts of cam 90 1101 to ground through the interrupter 1116.

A control circuit may be traced from battery, left winding of relay 703, conductor 730, lower contacts of cam 1236 to brush 1237 and in parallel therewith from battery, winding of relay 717, conductor 718, right contacts of cam 1217 to brush 1237, thence over terminal 1238, conductor 1239, resistances 1624 and 1625, conductor 1626, conductor 1801, upper 95 left contact of cam 1302 to ground at cam 1303 until sequence switch 1300 leaves position 9 and from conductor 1626 over the right back contact of relay 1800, conductor 1802, the lower left contact of cam 1302, to ground at cam 1303 after sequence switch 1300 reaches position 9 and until it leaves position 16. Relay 717 operates over this circuit but due to the high resistance 1625, relay 703 does not operate. 100

In response to the dial tone, the operator proceeds to dial the first code letter of the desired designation. Relay 1619 follows the dial impulses but relays 1611 and 1612 being slow to release remain energized during impulses. Upon the first de-energization of relay 1619 a circuit is established from ground at the back contact of relay 1619, right front contact of relay 1612, conductor 1627, right contacts of cam 1117, conductor 1118, winding of magnet 1901 of the A code register 1900 to battery and in parallel from battery, winding of relay 1623, over the upper contacts of cam 1117 to ground at the back contact of relay 1619. Relay 1623 operates and being slow to release remains operated until relay 1619 remains operated for an interval following the dialing of the first digit series. To insure that register 1900 will step accurately, relay 1702 operates in a 110 115 120 125 130

- circuit from battery, winding of relay 1702, conductor 1703, lower left and upper right contacts of cam 1119, conductor 1120, interrupter contacts 1902 of magnet 1901, conductor 1903, conductor 1112, right contacts of cam 1121, conductor 1118, right contacts of cam 1117, conductor 1627, right front contact of relay 1612 to ground at the back contact of relay 1619. Relay 1702 locks over the circuit previously traced to conductor 1627, thence over conductor 1628 to ground at its own front contact and holds the circuit of magnet 1901 closed until the magnet fully attracts its armature and opens its interrupter contact 1902, this holding circuit extending from battery, winding of magnet 1901, conductor 1118, right contacts of cam 1117, conductors 1627 and 1628 to ground at the front contact of relay 1702. When the first impulse ceases and relay 1619 re-operates the initial circuit of relay 1702 is opened and when magnet 1901 fully attracts its armature the locking circuit of relay 1702 is opened and relay 1702 releases, opening the pulse help circuit of magnet 1901. In this manner magnet 1901 responds to each impulse of the first digit series.
- When the last impulse of the first digit series has been transmitted to the magnet 1901 and relay 1619 remains momentarily operated, the circuit of slow-releasing relay 1623 is held open long enough to allow relay 1623 to release whereupon a circuit is established from ground at the back contact of relay 1623, back contact of relay 1615, which released when relay 1623 operated, conductor 1115, lower left contact of cam 1111, contact of cam 1110 to battery through the magnet winding of sequence switch 1100. Sequence switch 1100 advances from position $3\frac{1}{2}$ and in passing position $4\frac{1}{8}$ establishes a circuit for relay 1615, extending over the left front contact of relay 1612, conductor 1616, upper right contact of cam 1113 to ground at cam 1107. Relay 1615 operates, locking over a circuit through its winding, the left front contact of relay 1612, the right front contact of relay 1615 to ground at the back contact of relay 1623 and opening the circuit of sequence switch magnet 1100 whereupon the sequence switch is arrested in position $4\frac{1}{2}$. With sequence switch 1100 in position $4\frac{1}{2}$, when the operator dials the second code letter relay 1623 again operates from ground at the back contact of relay 1619 upon the release of this relay for the first impulse over the circuit previously traced, releasing relay 1615 and an impulse is transmitted from ground at the back contact of relay 1619, right front contact of relay 1612, conductor 1627, upper right and lower left contacts of cam 1117, conductor 1122 to battery through the winding of magnet 1911 of the B code register 1910. The circuit of relay 1702 is again established as traced to the lower left contact of cam 1119 thence over the lower right contact of this cam, conductor 1123, interrupter contacts 1912 of magnet 1911 thence to ground as traced at the back contact of relay 1619, and relay 1702 locks over the circuit established from its winding through the interrupter contacts 1912 of magnet 1911, conductor 1122, lower left and upper right contacts of cam 1117, conductors 1627 and 1628 to ground at the front contact of relay 1702. Relay 1702 and magnet 1911 respond to the impulses of the second digit series to record the second code digit on the B code register 1910.
- When the last impulse of the second digit series has been transmitted and relay 1619 remains operated, relay 1623 releases thereby establishing a circuit from ground, back contact of relay 1623, back contact of relay 1615, conductor 1115, lower left contact of cam 1111, contact of cam 1110 to battery through the magnet winding of sequence switch 1100 for advancing this sequence switch out of position $4\frac{1}{2}$. In passing through position $5\frac{1}{8}$, the circuit of relay 1615 previously traced is established over the upper right contact of cam 1113 and relay 1615 locks to the back contact of relay 1623 and opens the circuit of sequence switch magnet 1100 to arrest the sequence switch in position $5\frac{1}{2}$. With sequence switch 1100 in position $5\frac{1}{2}$, when the operator dials the third code digit series of the desired line designation, relay 1623 again operates, releasing relay 1615. When relay 1619 releases in response to the first impulse of the third digit series, an impulse is transmitted from ground at the back contact of relay 1619, right front contact of relay 1612, conductor 1627, upper right contact of cam 1117, upper left contact of cam 1124, conductor 1125, back contact of relay 1704, conductor 1705, winding of magnet 1921 of the C code register 1920 to battery. The circuit of relay 1702 is also established as traced to the lower left contact of cam 1119, upper left contact of cam 1119, conductor 1126, right back contact of relay 1704, conductor 1706, interrupter contacts 1922 of magnet 1921, conductor 1705, thence as traced to ground at the back contact of relay 1619. Relay 1702 locks over the circuit established from its winding, through interrupter contacts 1922 of magnet 1921, thence over conductor 1705, left back contact of relay 1704, conductor 1125, upper left contact of cam 1124, upper right contact of cam 1117 conductors 1627 and 1628 to ground at the front contact of relay 1702. Relay 1702 and magnet 1921 respond to the impulses of the third digit series to record the third code on the C register 1920.
- When the last impulse of the third code digit series has been transmitted and relay 1619 remains operated relay 1623 releases thereby establishing a circuit from ground,

back contact of relay 1623, back contact of relay 1615, conductor 1115, lower left contact of cam 1111, contact of cam 1110 to battery through the magnet winding of sequence switch 1100 for advancing this sequence switch out of position $5\frac{1}{2}$. When sequence switch 1100 passes through position $6\frac{1}{2}$ the previously traced circuit is established over the upper right contact of cam 1113 for relay 1615 which locks as previously described to ground at the back contact of relay 1623 and opens the circuit of the magnet of the sequence 1110 to arrest the sequence switch in position 7. When now the operator dials the thousands digit of the line designation and relay 1619 releases in response to the first impulse thereof, relay 1623 again operates, opening the locking circuit of relay 1615 which thereupon releases. An impulse is also transmitted from ground at the back contact of relay 1619, right front contact of relay 1612, conductor 1627, upper right contact of cam 1117, upper right contact of cam 1124, conductor 1127, magnet winding 1931 of thousands register 1930 to battery. The circuit of relay 1702 is also re-established as traced to the lower left contact of cam 1119, lower right contact of cam 1128, conductor 1129, interrupter contacts 1932 of magnet 1931, conductor 1127, thence as traced to ground at the back contact of relay 1619. Relay 1702 operates and locks over the circuit just traced from its winding through the interrupter contacts 1932, conductor 1127, upper right contact of cam 1124, conductors 1627 and 1628 to ground at the front contact of relay 1702. Relay 1702 and magnet 1931 respond to the impulses of the thousands digit series to record the hundreds digits on register 1940.

When the last impulse of the thousands digit series has been transmitted and relay 1619 remains operated, relay 1623 releases thereby establishing a circuit from ground, back contact of relay 1623, back contact of relay 1615, conductor 1115, lower left contact of cam 1111, contact of cam 1110 to battery through the magnet winding of sequence switch 1100 for advancing this sequence switch out of position 7. When sequence switch 1100 passes through position $7\frac{1}{2}$ the previously traced circuit is established over the upper right contact of cam 1113 for relay 1615 which locks as previously described to ground at the back contact of relay 1623 and opens the circuit of the sequence switch magnet to arrest sequence switch 1100 in position 8. When now the operator dials the hundreds digit of the line designation and relay 1619 releases in response to the first impulse thereof, relay 1623 again operates opening the locking circuit of relay 1615 which thereupon releases. An impulse is also transmitted from ground at the back contact of

relay 1619, right front contact of relay 1612, conductor 1627, upper right contact of cam 1117, lower right contact of cam 1124, conductor 1130, magnet winding 1941 of hundreds register 1940 to battery. The circuit of relay 1702 is also established as traced to the lower left contact of cam 1119, lower left contact of cam 1128, conductor 1131, interrupter contacts 1942 of magnet 1941, conductor 1130, thence as traced to ground at the back contact of relay 1619. Relay 1702 locks over the circuit just traced from its winding through the interrupter contacts 1942, conductor 1130, lower right contact of cam 1124, upper right contact of cam 1117, conductors 1627 and 1628 to ground at the front contact of relay 1702. Relay 1702 and magnet 1941 respond to the impulses of the hundreds digit series to record the hundreds digits on register 1940.

When the last impulse of the hundreds digit series has been transmitted and relay 1619 remains operated relay 1623 releases thereby establishing a circuit from ground, back contact of relay 1623, back contact of relay 1615, conductor 1115, lower left contact of cam 1111, contact of cam 1110 to battery through the magnet winding of sequence switch 1100 for advancing this sequence switch out of position 8. When sequence switch 1100 passes through position $8\frac{1}{2}$ the previously traced circuit for relay 1615 is established over the upper right contact of cam 1113 and relay 1615 locks as previously described to ground at the back contact of relay 1623 and opens the circuit of the sequence switch to arrest it in position 9. When now the operator dials the tens digit of the line designation and relay 1619 releases in response to the first impulse thereof, relay 1623 again operates opening the locking circuit of relay 1615 which thereupon releases. An impulse is also transmitted from ground at the back contact of relay 1619, right front contact of relay 1612, conductor 1627, upper right contact of cam 1117, lower left contact of cam 1124, conductor 1132, magnet winding 1951 of the tens register 1950 to battery. The circuit of relay 1702 is also established as traced to the lower left contact of cam 1119, upper left contact of cam 1128, conductor 1133, interrupter contacts 1952 of magnet 1951, conductor 1132, thence as traced to ground at the back contact of relay 1619. Relay 1702 locks over the circuit just traced from its winding through interrupter contacts 1952, conductor 1132, lower left contact of cam 1124, upper right contact of cam 1117, conductors 1627 and 1628 to ground at the front contact of relay 1702. Relay 1702 and magnet 1951 respond to the impulses of the tens digit series to record the tens digit on register 1950.

When the last impulse of the tens digit series has been transmitted and relay 1619

remains operated, relay 1623 releases thereby establishing a circuit from ground, back contact of relay 1623, back contact of relay 1615, conductor 1115, lower left contact of 5 cam 1111, contact of cam 1110 to battery through the magnet winding of sequence switch 1100 for advancing this sequence switch out of position 9. When sequence switch 1100 passes through position 9½ the 10 previously traced circuit for relay 1615 is established over the upper right contact of cam 1113 and relay 1615 locks to ground at the back contact of relay 1623 and opens the circuit of the sequence switch to arrest 15 it in position 10. The units digit dialed by the operator is now registered on the C code register 1920 which has by this time transferred its code registration to the translator. Before proceeding with the registration of 20 the units digit the setting of the translator in accordance with the registrations on the code registers 1900, 1910 and 1920 will first be described.

When sequence switch 1100 passed through 25 position 3½ for registering the A code digit on the code register 1900, a circuit was established from battery through the winding of relay 1606, conductor 1607, lower left contact of cam 1106 to ground at cam 1107 and an 30 obvious circuit was established for relay 1609 which holds open the circuit of relay 1707 extending from battery, winding of relay 1707, conductor 1708, normal contact and brush 1709 of translator 1710, conductor 35 1711, inner left contacts of relay 1609, conductor 1629, lower right contact of cam 1106 to ground at cam 1107. A similar circuit for relay 1712 over normal contact of brush 1713 of translator 1720 is also held open and 40 consequently when sequence switch 1100 reaches position 4½ the translators 1710 and 1720 are started. The driving circuit of translator 1710 may be traced from ground, back contact of relay 1707, magnet winding 45 1714, conductor 1715, right contacts of cam 1715 to battery. The driving circuit of translator 1720 may be traced from ground at the back contact of relay 1712, magnet winding 1716, conductor 1717 to battery at the left 50 contact of cam 1135.

If sequence switch 1100 has not passed position 5½ when either translator has advanced to a position marked by the setting of the A code register 1900, a circuit is established 55 for the stop relay 1707 or relay 1712 of the particular translator which first reaches the position marked. It will be assumed that translator 1710 first reaches the marked contact thus establishing the circuit 60 of relay 1707 extending from battery, winding of relay 1707, brush 1709 and the contact of its bank cross-connected to the bank terminal upon which brush 1904 of register 1900 65 is positioned, conductor 1136, upper right contact of cam 1137 to ground at cam 1107.

Had translator 1720 first reached the marked contact the circuit of stop relay 1712 would have been established from battery, winding of relay 1712, brush 1713 and the contact of its bank cross-connected to the bank terminal 70 upon which brush 1905 of register 1900 is positioned, conductor 1138, the lower left contact of cam 1139 to ground at cam 1107. Either relay 1707 or 1708 upon operating 75 opens the magnet circuit of its translator to arrest its further movement. The other hunting translator advances around into normal position where it is arrested through the operation of its stop relay. If it is assumed that translator 1710 is arrested on a terminal 80 marked by the A code register and translator 1720 advances on into normal position, translator 1720 is arrested by the operation of relay 1712 over the normal terminal and brush 1713 of translator 1720, conductor 1711, inner left back contact of relay 1609, conductor 1629, lower right contact of cam 1134 to ground at cam 1107, or, if it be assumed that translator 1720 is arrested on the 85 terminal marked by the A code register and 90 translator 1710 advances on into normal position translator 1710 is arrested by the operation of relay 1707 over the normal contact of brush 1709 and the circuit just traced.

When sequence switch 1100 passes beyond 95 position 5½, it being assumed that translator 1710 has been set in accordance with the setting of the A register, the circuit of relay 1707 is opened at the upper right contact of cam 1137 and relay 1707 releases restarting translator 1710. When sequence switch 1100 passes beyond position 6, the circuit of relay 1712 is opened at the lower right contact of cam 1106 and relay 1712 releases to restart translator 1720 from normal. Translator 100 1720 then rotates around into normal position again where it is arrested by the operation of relay 1712 over the normal contact of brush 1713, conductor 1711, lower left contact of cam 1140 to ground at cam 1107. When translator 1710 reaches a position determined by the setting of the B and C code registers 1910 and 1920, relay 1707 operates 105 in a circuit which may be traced in part from battery, winding of relay 1707, brush 1709 and the contact of its bank cross-connected to the terminal of the bank of register 1910 upon which brush 1914 thereof has been set, bank terminal and brush 1718 of translator 1710, conductor 1719, brush 1924 and the bank 110 terminal engaged thereby of register 1920, thence by cross-connection to the bank terminal engaged by brush 1721 of translator 1710, conductor 1722, lower right contact of cam 1140 to ground at cam 1107. Relay 1707 operates to arrest further movement of translator 1710 and closes an obvious circuit for relay 1723. When translator 1720 is arrested 115 in normal position and relay 1712 operates, relay 1724 does not operate as it is short- 120 125 130

circuited over brush 1725 and its normal contact conductor 1726 to ground over the upper right contact of cam 1140.

With relay 1723 operated, relay 1707 is locked operated over the inner left front contact of relay 1723, conductor 1727 to ground over the lower right contact of cam 1134 when sequence switch 1100 reaches position 7. The translator having now been set from the code 5 registers, the code register 1920 may now be released in readiness to record the units digit of the line designation as soon as the operator dials such designation. When relay 1723 operated, a circuit was established for relay 1704 10 extending from battery through its winding, outer left front contact of relay 1723, conductor 1728, lower right contact of cam 1141, conductor 1142, restoring bank and brush 1925 of register 1920 to ground. Relay 1704 15 upon operating extends its operating ground over its right front contact, conductor 1706, interrupter contacts 1922 and magnet winding 1921 of register 1920 to battery, thus advancing register 1920 into normal position, when 20 the circuit of relay 1704 is opened at brush 1925 and the operating circuit of magnet 1921 is opened. The setting of the translator and the restoration of register 1920 will have taken 25 place while the operator was dialing the thousands, hundreds and tens digits so that by the time she dials the units digit the register 1920 30 will be restored ready to register such digit.

When the operator dials the units digit, sequence switch 1100 having been advanced 35 into position 10, and relay 1619 releases in response to the first impulse thereof, relay 1623 again operates, opening the circuit of relay 1615 which thereupon releases. An impulse is also transmitted from ground at the back 40 contact of relay 1619, right front contact of relay 1612, conductor 1627, upper right contact of cam 1117, upper left contact of cam 1124, conductor 1125, left back contact of relay 1704, conductor 1705, winding of magnet 1921 of the register 1920 to battery. The circuit of relay 1702 is also established as traced 45 to the lower left contact of cam 1119, upper left contact of cam 1119, conductor 1126, right back contact of relay 1704, conductor 1706, in- 50 terrupter contacts 1922 of magnet 1921, conductor 1705, left back contact of relay 1704, thence to ground at the back contact of relay 1619. Relay 1702 locks over the circuit just traced from its winding through the inter- 55 rupter contacts 1922 of magnet 1921, conductor 1705, left back contact of relay 1704, conductor 1125, upper left contact of cam 1124, upper right contact of cam 1117, conductors 1627 and 1628 to ground at the front contact 60 of relay 1702. Relay 1702 and magnet 1921 respond to the impulses of the units digit series to record the units digit on register 1920. The entire line designation dialed by 65 the operator has now been registered in the sender and since the present invention is not

concerned with the extension of a connection under the control of the registration set up, no detailed description of the further functioning of the sender, the functioning of selector switches controlled thereby and the release of an established connection will be given. 70

Registration controlled by keyset

If the operator desires to extend a connection by using her keyset 111 she first depresses dialing key 103 and then inserts plug 101 into the trunk jack 102. A circuit is then established from ground at the outer right alternate contacts of key 103 over the sleeve 80 contacts of plug 101 and jack 102 to battery through the winding of relay 112. Relay 112 operates in turn closing an obvious circuit for relay 113 which in turn causes the operation of relay 114. A circuit is also established from battery over the left back contact of relay 115, left alternate contacts of key 103, tip contacts of plug 101 and jack 102, winding of relay 106 to ground at the right back contact of relay 105. Relay 106 85 receives sufficient current to operate and closes an obvious circuit for relay 109 which at its inner left front contact connects ground to the circuit just traced through the winding of relay 106 to hold relay 106 operated following the removal of ground from its circuit by the later operation of relay 105, which latter relay operates in parallel with relay 108 over a circuit extending from battery 90 through the windings of these relays, the right alternate contacts of relay 109 to ground at the inner right normal contacts of relay 116. Relay 105 upon operating disconnects the winding of relay 104 but relay 108 is without function at this time. 95

Relay 109 closes a circuit from battery, outer left front contact of relay 109, resistance 118, resistance 119 to ground through the winding of group relay 117 and places calling potential on terminal 201 in the banks 100 of all line finders such as 200 having access to trunk circuit 110. Relay 117 upon operating closes a circuit extending from ground at its front contact, over conductor 120 to battery through the winding of start relay 401. Relay 401 in turn closes an obvious circuit through the windings of relays 402 and 403, relay 402 in turn closing an obvious circuit for relay 404. Relay 404 closes circuits in parallel through start relays such as 405. Relay 403 upon operating closes driving circuits for all district link finders such as 400 having access to the line finder 110 district selector link such as that disclosed 115 in Figs. 2 and 3. The circuit of the driving magnet 410 of the link finder 400 may be traced from battery, winding of magnet 410, front contact of relay 403, conductor 406, upper contacts of cam 501, conductor 502, 120

130

intermediate normal contacts of jack 407 to ground at the back contact of relay 408.

As soon as the link finder 400 finds an idle link circuit a circuit is established for relay 408 extending from battery, upper contacts of cam 301, conductor 302, terminal 411 and brush 412, upper normal contacts of jack 407, outer right contact of relay 405, conductor 409, upper right and lower left contacts of cam 503, conductor 504 to ground through the right winding of relay 408. Relay 408 operates opening the circuit of magnet 410 and closing an obvious circuit for relay 413. At its inner left front contact relay 413 connects ground through the left winding of relay 407, thereby holding relay 406 operated and reducing the potential on terminal 411 to hold the selected link unselectable to other link finders. At its inner right front contact relay 413 closes a circuit extending from battery, right winding of relay 202, conductor 203, right contacts of cam 303, conductor 304, terminal 414, brush 415, conductor 416, inner right front contact of relay 413, conductor 417, upper right contact of cam 505 to ground at cam 506. Relay 202 operates and closes a circuit for magnet 204 from battery, conductor 205, right contacts of cam 305, conductor 306, right front contact of relay 202, conductor 206, upper right and lower left contacts of cam 307, conductor 308, back contact of relay 207, conductor 208, lower left contact of cam 309 to ground at cam 311.

Magnet 204 advances the brushes of line finder 200 until brush 231 engages terminal 201, upon which selectable potential has been placed by relay 109, when battery on terminal 201 is extended over brush 231, conductor 209, upper contacts of cam 312, conductor 313 to ground through the right winding of relay 207. Relay 207 operates opening the circuit of magnet 204 to thereby arrest finder 200 on the terminals of trunk 110. With relay 207 operated a circuit is extended from battery on terminal 201, brush 231, conductor 209, right and lower left contacts of cam 312, conductor 314, middle winding of relay 207, right winding of relay 210, conductor 211, upper right and lower left contacts of cam 315, conductor 316, front contact of relay 207, conductor 208, lower left contact of cam 309 to ground at cam 311. Relay 210 operates in this holding circuit closing a circuit extending from battery, winding of relay 212, conductor 213, left contacts of cam 317, conductor 318 to ground at the contact of relay 210. Relay 212 upon operating closes a circuit for advancing sequence switch 319 into position 2 which circuit extends from battery, magnet winding of the sequence switch, contacts of cam 320, lower left contact of cam 321, conductor 322, left front contact of relay 212, conductor 310, upper right contact of cam 309 to ground at cam 311. At its outer right front contact relay 212 connects battery

through the lower left contact of cam 301 over conductor 323, conductor 214 to conductor 302 to replace battery through the upper left contact of cam 301 after sequence switch 319 leaves position 1. At its inner right front contact relay 212 establishes a circuit from battery, resistance 215, inner right back contact of relay 216 to ground through the winding of relay 217 and relay 217 operates but without function at this time. When sequence switch 319 leaves position 1, relays 212 and 217 release.

When relay 207 operated and connected its middle winding in parallel with its right winding to brush 208 thereby reducing the potential on terminal 201, relay 117 became shunted to such an extent that it released, in turn releasing relays 401, 402, 403, 404 and 405, relay 403 opening the driving circuit of all other hunting link finders and relay 405 opening the circuit previously traced through the winding of relay 408. Relay 408 is, however, held operated over the middle right front contact of relay 417 which is in parallel with the right contact of relay 408, relay 417 having operated upon the operation of relay 210 over a circuit from ground at the front contact of relay 210, conductor 318, upper right contact of cam 317, conductor 324, terminal 418, brush 419, conductor 420, upper left and lower right contacts of cam 507, conductor 508, middle right front contact of relay 413 to battery through the winding of relay 417, relay 417 locking over its inner right front contact, conductor 420, brush 419, terminal 418, contacts of cam 317 to ground at the front contact of relay 210 independent of the contacts of relay 413. Relay 417 closes a circuit for relay 800 extending from battery, winding of relay 800, conductor 801 to ground at the outer left front contact of relay 417. At its inner left front contact relay 800 closes a circuit for advancing sequence switch 500 out of position 1 into position 2½ extending from battery, winding of the magnet of sequence switch 500, contact of cam 509, upper right contact of cam 510, conductor 511, inner left front contact of relay 800, conductor 802, brush 421, terminal 422, conductor 325, lower right and left contacts of cam 326, conductor 318 to ground at the front contact of relay 210. As soon as sequence switch 500 leaves position 1, the circuit of relay 408 is opened at contacts of cam 503 and relay 408 releases opening the circuit of relay 413 which also releases in turn opening the circuit of relay 202. With relay 202 released sequence switch 319 is advanced into position 4 over a circuit extending through its winding, contact of cam 320, upper left contact of cam 326, conductor 327, right back contact of relay 202, conductor 206, upper left contact of cam 309 to ground at cam 311.

With relay 202 released and sequence switch 319 in position 4 a circuit is now es-

tablished for relay 116 in parallel with resistance 121, conductor 122, terminal 218, brush 219, right winding of relay 216, conductor 220, right contacts of cam 328, conductor 329 to ground at the inner left back contact of relay 202. Relay 216 operates and locks over its left winding and inner left front contact, conductor 206, upper left contact of cam 309 to ground at cam 311. At its outer contacts relay 116 introduces resistances 123 and 124 into the impulsing leads extending to the operator's position and at its inner right front contact transfers the operating ground for relays 105 and 108 to conductor 125 over terminal 221, brush 222, winding of relay 223, outer left back contact of relay 202, conductor 224 to ground over the upper left contact of cam 311. Relay 223 operates in this holding circuit establishing a circuit from battery, winding and right normal contacts of relay 115, right alternate contacts of key 103, ring contacts of plug 101 and jack 102, resistance 124, terminal 225, brush 226, right front contact of relay 223, conductor 227, lower right contact of cam 330, conductor 331, terminal 423, brush 424, conductor 425, outer right front contact of relay 417, conductor 426, upper contacts of cam 512, conductor 513, choke coil 427, winding of relay 428 to ground. Relay 115 operates in this circuit locking over its outer right front contact to ground at the right contacts of key 103, opening its own operating circuit, lighting lamp 138 and opening the circuit of relay 106. Relay 106 releases in turn releasing relay 109, relays 105 and 108 now being held operated over the right normal contacts of relay 109 thence as traced over conductor 125 independent of contacts of relay 116.

With sequence switch 319 in position 4 and sender sequence switch 500 in position 2 1/2, upon the illumination of lamp 138, the operator proceeds to write up on the keys of her keyset 111 the digits of the desired line designation. For the purposes of this description it will be assumed that she writes up the designation CHE-5678. The keys of the keyset are arranged to connect either direct or alternating current or a combination of both to either or both of the talking conductors of the cord circuit and trunk circuit to the windings of the direct current relays 428 and 429 or to the windings of the alternating current relays 430 and 431 of the sender. It having been assumed that the first code letter of the desired line designation is C, the operator depresses key 126 thereby connecting direct current through resistance 127, right contacts of key 126, right alternate contacts of key 103, ring contacts of plug 101 and jack 102, resistance 124, terminal 225, brush 226, right front contact of relay 223, conductor 227, right contact of cam 330, conductor 331, terminal 423, brush 424, outer right front

contact of relay 417, conductor 426, upper contacts of cam 512, conductor 513, choke coil 427 to ground through the winding of relay 428. A branch of this circuit extends through condenser 432 to ground through the winding of relay 431, but due to the condenser relay 431 does not operate by the direct current. Relay 428 operates and closes a circuit extending from ground at its contact, conductor 434, inner right back contact of relay 1000, winding of relay 1002 of the A code register to battery. Relay 1002 operates and locks over its inner left front contact, conductor 1003, lower left and upper right contacts of cam 514, conductor 515 to ground through the winding of relay 1004. Relay 1004, however, is shunted by ground at the front contact of relay 428 until the operator releases key 126 and therefore does not operate. Since relays 429, 430, and 431 were not operated when key 126 was depressed register relays 1005, 1006 and 1007 of the A code register do not operate.

When the operator releases key 126 relay 1004 operates in the locking circuit of register 1002 and closes an obvious circuit for transfer relay 1000 which at its back contacts disconnects the windings of the register relays of the A code register from the circuits extending through the front contacts of control relays 428, 429, 439 and 440 and at its front contacts prepares circuits for the register relays of the B code register. When now the operator depresses key 128 for the second code letter H, a circuit is established from ground through the left winding of coil 129, left contacts of key 128, left alternate contacts of key 103, tip contacts of plug 101 and jack 102, contacts of relay 108, left back contact of relay 109, resistance 123, conductor 131, terminal 228, brush 229, left contact of relay 223, conductor 230, lower right contact of cam 332, conductor 333, terminal 446, brush 447, inner left front contact of relay 417, outer left back contact of relay 436, conductor 437, left contacts of cam 516, conductor 517, condenser 433 to ground through the winding of relay 430. Alternating current is induced into the circuit through the middle winding of coil 129 from the source of alternating current 130. Relay 430 responds to this current, but relay 429 which is connected in parallel with the winding of relay 430 does not operate because of the inclusion of the choke coil 438 in series therewith.

Relay 430 upon operating closes an obvious circuit for relay 439 which closes a circuit extending from ground at its front contact over conductor 441, inner left front contact of relay 1000, inner left back contact of relay 1010, winding of register relay 1016 to battery. Relay 1016 operates and locks over its inner left front contact, conductor 1113, winding of relay 1014, conductor 1008, upper right

contact of cam 518 to ground at cam 506. Relay 1014 does not operate in this locking circuit until the depressed key 128 is released as it is shunted by ground at the front contact 5 of relay 439. When the key is released and relays 430 and 439 release, relay 1014 operates closing an obvious circuit for transfer relay 1010, which at its back contacts disconnects the windings of the relays of the B code 10 register from the control circuits extending through the contacts of control relays 428, 429, 439 and 440 and at its front contacts prepares control circuits for the relays of the C code register. Since only control relay 430 15 and the auxiliary relay 439 were operated when key 128 was depressed the other relays 1012, 1015 and 1017 of the B code register were not operated.

When now the operator depresses key 132 20 for the third code letter E a circuit is established from battery through the right winding of coil 129, left contacts of key 132, thence as traced to ground through the condenser 433 and winding of relay 430 and in parallel 25 through choke coil 438 to ground through the winding of relay 429. Relay 429 due to the connection of direct current at the depressed key will now operate and since alternating current is inductively impressed upon 30 the right winding of coil 129 from source 130, relay 430 will also operate in turn operating relay 439. Two circuits are now established, one extending from ground at the front contact of relay 429, conductor 442, outer left 35 front contacts of transfer relays 1000 and 1010, conductor 1018, outer left back contact of relay 1500, winding of register relay 1505 to battery, and the other circuit extending from ground at the front contact of relay 439, thence as traced over the inner left front 40 contacts of transfer relays 1000 and 1010, conductor 1011, inner left back contact of relay 1500 to battery through the winding of register relay 1506. Relays 1505 and 1506 operate 45 and lock over their inner contacts through the winding of relay 1504 to ground on conductor 1008 but relay 1504 being shunted over the front contacts of relays 429 and 439 does not operate until the depressed key is released. When the key is released and relays 429, 430, and 439 release, relay 1504 operates 50 closing an obvious circuit for transfer relay 1500 which at its back contacts disconnects the relays of the C code register from the control 55 circuits extending through contacts of control relays 428, 429, 439 and 440 and at its front contacts prepares control circuits for the relays of the thousands register. Since only control relays 429 and 430 and 60 auxiliary control relay 439 were operated when key 132 was depressed, the other relays 1502 and 1507 of the C code register were not operated.

When now the operator depresses key 133 65 for the thousands digit 5, a circuit is estab-

lished from battery, through resistance 127, the left contacts of key 133, thence as traced through choke coil 438 to ground through the winding of relay 429. Since no alternating current is impressed upon this circuit relay 430 which is connected in parallel with the winding of relay 429 through condenser 433 does not operate. A second circuit is also established from ground, left winding of coil 129, right contacts of key 133, thence as traced through choke coil 427 and winding of relay 428 to ground and in parallel through condenser 432 and winding of relay 431 to ground. Relay 428 does not operate since no battery is connected to its operating circuit 70 but since alternating current is impressed on the left winding of coil 129 from the source of alternating current 130, relay 431 operates causing the operation of the auxiliary control relay 440. Two circuits are now established, 75 the first extending from ground at the front contact of relay 429, conductor 442, outer left front contacts of relays 1000 and 1010, conductor 1018, outer left front contact of relay 1500, outer left back contact of relay 1510, 80 through the winding of relay 1515 to battery and the second circuit extending from ground at the front contact of relay 440, conductor 443, outer right front contacts of relays 1000 and 1010, conductor 1019, outer right front contact of relay 1500, outer right back contact of relay 1510 to battery through the winding of relay 1517. Register relays 1515 and 1517 85 operate and lock over their front contacts through the winding of relay 1514, conductor 1508, lower right contact of cam 518 to ground at cam 506, but relay 1514 being shunted over the front contacts of relays 429 and 440, does not operate until the depressed key is released. When the key is released and relays 429, 431 90 and 440 release, relay 1514 operates closing an obvious circuit for transfer relay 1510. Relay 1510 at its back contacts disconnects the relays of the thousands code register from the control circuits extending through contacts of control relays 428, 429, 439 and 440 and at its front contacts prepares control circuits for the relays of the hundreds register. No operating circuits for relays 1512 and 1516 95 of the thousands register having been closed, these relays remain unoperated.

When now the operator depresses key 134 100 for the hundreds digit 6 a circuit is established from battery through the right winding of coil 129, over the right contacts of key 134 thence as traced through choke coil 427, winding of relay 428 to ground. Relay 428 105 operates and since alternating current is impressed from source 130 upon the right winding of coil 129, relay 431 also operates in turn operating auxiliary relay 440. Two circuits are now established, the first extending from ground at the front contact of relay 428, over conductor 434, the inner right front contacts 110 of relays 1000 and 1010, conductor 1009, the 115

inner right front contacts of relays 1500 and 1510, the inner right back contact of relay 1520, winding of relay 1522 of the hundreds register to battery and the second circuit extending from ground at the front contact of relay 440, conductor 443, outer right front contacts of relays 1000 and 1010, conductor 1019, outer right front contacts of relays 1500 and 1510, outer right back contacts of relay 1520 to battery through the winding of register relay 1527. Relays 1522 and 1527 lock over their inner right front contacts through the winding of relay 1524 to ground on conductor 1508 but relay 1524 being shunted by ground at the front contacts of relays 428 and 440 does not operate until the depressed key 134 is released and relays 428, 431 and 440 release. When relay 1524 operates an obvious circuit is established for transfer relay 1520 which at its right back contacts opens the control circuits extending from front contacts of relays 428, 429, 439, and 440 to windings of the hundreds register relays and prepares control circuits over its front contacts for the relays of the tens register. No operating circuits for relays 1525 and 1526 having been closed, these relays remain unoperated.

When the operator depresses key 135 for the tens digit 7 a circuit is established from battery over the left contacts of key 135 thence as traced through choke coil 438, to ground through the winding of relay 429 and a second circuit is established from battery over the right winding of coil 129, right contacts of key 135, thence as traced through choke coil 427 to ground through the winding of relay 428. Relays 428 and 429 operate and since alternating current is impressed from source 130 upon the right winding of coil 129, relay 431 also operates in turn operating relay 440. Three circuits are now established, the first extending from ground at the front contact of relay 429 over conductor 442, the outer left front contacts of relays 1000 and 1010, conductor 1018, the outer left front contacts of relays 1500, 1510 and 1520, conductor 1509, the outer left back contact of relay 2000 to battery through the winding of tens register relay 2005. The second circuit extends from ground at the front contact of relay 428, over conductor 434, the inner right front contacts of relays 1000 and 1010, conductor 1009, the inner right front contacts of relays 1500, 1510 and 1520, conductor 1513, the inner right back contact of relay 2000 to battery through the winding of register relay 2002. The third circuit extends from ground at the front contact of relay 440, conductor 443, outer right front contacts of relays 1000 and 1010, conductor 1019, outer right front contacts of relays 1500, 1510, 1520, conductor 1511, the outer right back contact of relay 2000 to battery through the winding of register relay 2007. Relays 2002, 2005 and 2007 lock over their inner

front contacts through the winding of relay 2004, conductor 2003, upper left contacts of cam 518 to ground at cam 506, but relay 2004 being shunted by ground at the front contacts of relays 428, 429 and 440 does not operate until the depressed key 135 is released and relays 428, 429 and 440 release. When relay 2004 operates an obvious circuit is established for transfer relay 2000 which at its back contacts opens the control circuits extending from front contacts of relays 428, 429, 439 and 440 to windings of the tens register relays and prepares control circuits over its front contacts for the relays of the units register. Register relay 2006 remains unoperated.

The operator now depresses the key 136 for the units digit 8 establishing a circuit from ground through the left winding of coil 129, left contacts of key 136, thence as traced to ground through the winding of relay 430 and a second circuit from ground through the left winding of coil 129, right contacts of key 136 thence as traced to ground through the winding of relay 431. Since no battery is connected to these circuits, relays 429, and 428 do not operate but relays 430 and 431 operate by alternating current impressed from the source 130 on the circuits traced. Relays 430 and 431 close obvious circuits for relays 439 and 440, relay 439 closing a circuit from ground at its front contact over conductor 441, the inner left front contacts of relays 1000 and 1010, conductor 1011, the inner left front contacts of relays 1500, 1510 and 1520, conductor 1503, the inner left front contacts of relay 2000, the inner left back contact of relay 2010 to battery through the winding of units register relay 2016. Relay 440 closes a circuit extending from ground at its front contact over conductor 443, outer right front contacts of relays 1000 and 1010, conductor 1019, outer right front contacts of relays 1500, 1510 and 1520, conductor 1511, the outer right front contact of relay 2000, the outer right back contact of relay 2010 to battery through the right winding of relay 2017. Relay 2017 upon operating locks over both of its windings and its inner left front contact to ground on conductor 2003 and relay 2016 locks over its inner left front contact through the winding of relay 2014 to ground on conductor 2003, but relay 2014 being shunted by ground at the front contacts of relays 439 and 440 does not operate until the depressed key 136 is released and relays 430, 431, 439 and 440 release. When relay 2017 operates an obvious circuit is established for transfer relay 2010 which at its back contacts opens the control circuits extending from front contacts of relays 428, 429, 439 and 440 to windings of the units register relay and prepares control circuits over its right front contacts for reoperating the A code register relay.

Register relays 2012 and 2015 are not operated.

From the foregoing it will be observed that the relays of each register, taking the A code 5 digit register as an example, are operated in the following combinations to register the digits 0 to 9, inclusive.

Digits Relays operated

10	0	1007
	1	1005, 1002
	2	1002
	3	1005, 1006
	4	1006
15	5	1005, 1007
	6	1002, 1007
	7	1005, 1002, 1007
	8	1006, 1007
	9	1005, 1006, 1007

20 As soon as the first or A code letter was registered and relay 1004 operated, a circuit was established for advancing sequence switch 500 into position 4 extending from ground at the left front contact of relay 1004, conductor 1020, lower right contact of cam 510, contact of cam 509 to battery through the magnet winding of the sequence switch. With sequence switch 500 in position 4, a circuit is established for advancing the secondary A code register 1400 extending from battery, winding of magnet 1401, interrupter contacts 1402, conductor 1403, lower contacts of cam 519, conductor 520, back contact of relay 444, conductor 445, upper contacts of cam 524 to ground. Magnet 1401 thereupon advances the brushes of register 1400 until brush 1404 engages a terminal of its bank which is marked by the setting of the registers of the A code register. It having been assumed that the relay 1002 of the A code register was operated to register the code letter C, having a numerical equivalent of 2, then when brush 1404 engages terminal 1405 a circuit is established from battery, right back contact of register relay 1007, inner right front contact of relay 1002, outer left back contact of relay 1005, conductor 1406, terminal 1405, brush 1404, conductor 1407, lower contacts of cam 521, conductor 522, winding of relay 444, conductor 449, upper right contact of cam 526 to ground at cam 506. Relay 444 operates opening the circuit of magnet 1401 to arrest further movement of register 1400 and closes a circuit from ground on conductor 445, conductor 448, lower right contact of cam 523 to battery through the magnet winding of sequence switch 500 for advancing the sequence switch into position 7. Register 1410 has now taken a setting in accordance with the setting of the B code register.

25 25 As soon as the first or A code letter was registered and relay 1004 operated, a circuit was established for advancing sequence switch 500 into position 4 extending from ground at the left front contact of relay 1004, conductor 1020, lower right contact of cam 510, contact of cam 509 to battery through the magnet winding of the sequence switch. With sequence switch 500 in position 4, a circuit is established for advancing the secondary A code register 1400 extending from battery, winding of magnet 1401, interrupter contacts 1402, conductor 1403, lower contacts of cam 519, conductor 520, back contact of relay 444, conductor 445, lower right contact of cam 523 to battery through the magnet winding of sequence switch 500 for advancing the sequence switch into position 5 $\frac{1}{2}$. Register 1400 has now taken a setting in accordance with the setting of the A code register. Upon reaching position 5, sequence switch 500 holds transfer relay 1000 operated independently of relay 1004 over conductor

529 to ground at the upper right contact of cam 506. In position 5 $\frac{1}{2}$ sequence switch 500 opens the circuit of relay 1004 and the locking circuit of the operated register relay 1002 and these relays release.

70 A circuit is now established as soon as the B code register is set and relay 1014 operates for setting the secondary code register 1410 which circuit may be traced from battery, winding of magnet 1411, interrupter contacts 1412, conductor 1413, upper right contact of cam 519, conductor 520, back contact of relay 444, which released when sequence switch 500 left position 4 $\frac{1}{2}$, conductor 445, lower right contact of cam 524, conductor 525 to ground at the left contact of relay 1014. Magnet 1411 thereupon advances the brushes of register 1410 until brush 1414 engages a terminal in its bank which is marked by the setting of the relays of the B code register. It having been assumed that the relay 1016 of the B code register was operated to register code letter H, having a numerical equivalent of 4, then when brush 1414 engages terminal 1415 a circuit is established from battery, right back contact of register relay 1017, inner right front contact of relay 1016, inner left back contact of relay 1015, conductor 1416, terminal 1415, brush 1414, conductor 1417, upper left contact of cam 521, conductor 522, winding of relay 444, conductor 449, upper right contact of cam 526 to ground at cam 506. Relay 444 operates opening the circuit of magnet 1411 to arrest further movement of register 1410 and closes a circuit from ground on conductor 445, conductor 448, lower right contact of cam 523 to battery through the magnet winding of sequence switch 500 for advancing the sequence switch into position 7. Register 1410 has now taken a setting in accordance with the setting of the B code register.

75 80 85 90 95 100 105 110 115 120 125 130 A circuit is now established as soon as the C code register is set and relay 1504 operates for setting the secondary code register 1420, which circuit may be traced from battery, winding of magnet 1421, interrupter contacts 1422, conductor 1423, upper left contact of cam 519, conductor 520, back contact of relay 444, which released when sequence switch 500 left position 6, conductor 445, lower left contact of cam 524, conductor 527 to ground at the left front contact of relay 1504. Magnet 1421 thereupon advances the brushes of register 1420 until brush 1424 engages a terminal in its bank which is marked by the setting of the relays of the C code register. It having been assumed that the C code register was operated to register the code letter E, having a numerical equivalent of 3, then when brush 1424 engages terminal 1425 a circuit is established from battery, right back contact of register relay 1507, inner right front contact of relay 1506, outer left front contact of

relay 1505, conductor 1426, terminal 1425, brush 1424, conductor 1427, upper right contact of cam 521, conductor 522, winding of relay 444, conductor 449, upper right contact of cam 526 to ground at cam 506. Relay 444 operates opening the circuit of magnet 1421 to arrest further movement of register 1420 and closes a circuit from ground on conductor 445, over conductor 448, lower right contact of cam 523 to battery through the magnet winding of sequence switch 500 for advancing the sequence switch into position 9. The entire code registration has now been transferred to the secondary code registers in preparation for the usual translation and the operated relay of the A code register have been released.

Having keyed the entire line designation, the operator restores key 103 thereby releasing relays 115 and 112, relay 112 in turn releasing slow-to-release relay 113 which in turn releases slow-to-release relay 114. During this delayed releasing period battery is connected over the front contacts of relay 114 and the back contacts of relay 112 to ground through the windings of control relays 428 and 429 which momentarily operate. Relay 428 upon operating closes a circuit from ground over conductor 434, inner right front contacts of relays 1000, 1010, 1500, 1510, 1520, 2000 and 2010, conductor 2008 to battery through the winding of the A code register relay 1002 which locks over its inner left front contact, conductor 1003, left contacts of cam 514, conductor 528 to ground through the winding of relay 450, but relay 450 does not operate since it is shunted to ground at the front contact of relay 428. As soon, however, as relay 428 release upon the release of slow-to-release 114 relay 450 operates. Relay 429 upon operating closes a circuit from ground at its front contact over conductor 442, the outer left front contacts of relays 1000, 1010, 1500, 1510, 1520, 2000 and 2010, conductor 2011, upper right contact of cam 523 to battery through the magnet winding of sequence switch 500 for advancing sequence switch 500 into position 11 in which position it remains until the sender has completed the setting of selector switches in accordance with the register designation.

The sender is now in condition to control selections in accordance with the registration set up therein but since the present invention is not concerned with the manner in which selections are controlled by the sender or with the release of the established connections no further description of those operations will be given herein.

Although in the foregoing description it has been assumed that the private branch exchange operator has controlled the registration of the designation of a connection by using either her position dial 100 or her keyset 111, it will be apparent that local sub-

scribers in the private branch exchange may also control the establishment of connections by dialing in the usual manner. Such subscribers in initiating connections would have access to the sender of Figs. 11, 13, 16, 17, 18 and 19 over line finders 600 and 700 of Figs. 6 and 7, these line finders being started in the well known manner to find the calling lines which terminate in the bank of line finder 600.

What is claimed is:

1. In a telephone exchange system an operator's position, an impulse dial and a keyset at said position, a trunk circuit and switching mechanism for extending connections from said position, sending mechanism for controlling said switching mechanism having registers for recording the designations of desired connections, and means for controlling said registers from said dial or from said keyset.

2. In a telephone exchange system an operator's position, an impulse dial and a keyset at said position, a trunk circuit and switching mechanism for extending connections from said position, sending mechanism for controlling said switching mechanism having registers for recording the designations of desired connections, a key at said position for connecting either said dial or said keyset to said trunk circuit, and means in said trunk circuit controlled by said key for rendering said registers controllable from said dial or from said keyset.

3. In a telephone exchange system an operator's position, an impulse dial and a keyset at said position, a trunk circuit and switching mechanism for extending connections from said position, sending mechanism for controlling said switching mechanism having registers for recording the designations of desired connections, means at said position for selecting either said dial or keyset for use, and means controlled by said selecting means for determining whether registers of said sending mechanism shall be set from said dial or from said keyset.

4. In a telephone exchange system an operator's position, an impulse dial and a keyset at said position, a trunk circuit and switching mechanism for extending connections from said position, sending mechanism for controlling said switching mechanism having registers for recording the designations of desired connections, means at said position for selecting either said dial or keyset for use, and means in said trunk circuit controllable by said selecting means for determining whether registers of said sending mechanism shall be set from said dial or from said keyset.

5. In a telephone exchange system an operator's position having a cord circuit, an impulse dial normally associated with said cord circuit, a keyset at said position, a key

at said position for disconnecting said dial and for connecting said keyset with said cord circuit, a trunk circuit accessible to said cord circuit, switching mechanism accessible from 5 said trunk circuit for extending connections from said position, sending mechanism for controlling said switching mechanism having registers for recording the designations of desired connections, and discriminating 10 means in said trunk circuit controlled in accordance with the non-operated or operated condition of said key when said cord circuit is connected to said trunk circuit for determining whether 15 registers of said sending mechanism shall be set from said dial or from said keyset.

6. In a telephone exchange system an operator's position, an impulse dial and a keyset at said position, a trunk circuit accessible from 20 said position, a first sender for controlling the extension of connections having registering mechanism responsive to dial impulses, a second sender for controlling the extension of connections having registering mechanism 25 responsive to control from said keyset, means for connecting either one of said senders with said trunk circuit, and means in said trunk circuit controlled from said position in accordance with whether the operator takes 30 the impulse dial or the keyset for use for determining whether said first or said second sender shall be connected to said trunk circuit.

7. In a telephone exchange system an operator's position, an impulse dial and a keyset at said position, a trunk circuit accessible from said position, a first sender for controlling the extension of connections having registering mechanism responsive to dial impulses, a second sender for controlling the extension of connections having registering mechanism responsive to control from said keyset, means for connecting either one of said senders with said trunk circuit, a key 45 at said position for connecting either said dial or said keyset to said trunk circuit, and means in said trunk circuit controlled by said key for determining whether said first or said second sender shall be connected to said 50 trunk circuit.

8. In a telephone exchange system an operator's position having a cord circuit, an impulse dial normally associated with said 55 cord circuit, a keyset at said position, a key at said position for disconnecting said dial and for connecting said keyset with said cord circuit, a trunk circuit accessible to said cord circuit, a first sender for controlling the extension of connections having registering mechanism responsive to dial impulses, a second sender for controlling the extension of connections having registering mechanism responsive to control from said keyset, means 60 for connecting either one of said senders with

said trunk circuit, and discriminating means in said trunk circuit controlled in accordance with the non-operated or operated condition of said key when said cord circuit is connected to said trunk circuit for determining whether 70 said first or said second sender shall be connected to said trunk circuit.

9. In a telephone exchange system an operator's position, an impulse dial and a keyset 75 at said position, a trunk circuit accessible from said position, first senders for controlling the extension of connections having registering mechanism responsive to dial impulses, second senders for controlling the extension of connections having registering mechanism responsive to control from said keyset, a first group of link circuits including line finders for associating an idle one of said first senders with said trunk circuit, a second group of link circuits including line finders for associating an idle one of said second senders with said trunk circuit, and means in said trunk circuit controlled from said position in accordance with whether the operator takes the impulse dial or the keyset for use for determining whether a link circuit of the first group or a link circuit of the second group shall be used to connect a sender with said trunk circuit.

10. In a telephone exchange system an operator's position, a keyset at said position, a trunk circuit and switching mechanism for extending connections from said position, a plurality of register senders common to said trunk circuit for controlling said switching mechanism, means for associating an idle sender with said trunk circuit, and means controllable from said keyset over two conductors of said trunk circuit by impulses of direct and alternating current for setting the registers of said sender.

11. In a telephone exchange system, an operator's position, a keyset at said position, a trunk circuit and switching mechanism for extending connections from said position, a plurality of register senders common to said trunk circuit for controlling said switching mechanism, means for associating an idle sender with said trunk circuit, and means controllable from said keyset over two conductors of said trunk circuit by impulses of either direct or alternating current applied over either or both of said conductors for setting the registers of said sender.

12. In a telephone exchange system an operator's position, a keyset at said position, a trunk circuit and switching mechanism for extending connections from said position, a plurality of register senders common to said trunk circuit for controlling said switching mechanism, means for associating an idle sender with said trunk circuit, and means controllable from said keyset over two conductors of said trunk circuit by impulses of either direct or alternating current of a com- 125 130 135 140 145 150 155 160 165 170 175 180 185 190 195 200 205 210 215 220 225 230 235 240 245 250 255 260 265 270 275 bination of both over either of said conductors for setting the registers of said sender.

13. In a telephone exchange system an operator's position, a keyset at said position, a 5 trunk circuit and switching mechanism for extending connections from said position, a plurality of register senders common to said trunk circuit for controlling said switching mechanism, means for associating an idle 10 sender with said trunk circuit, and means controllable from said keyset over two conductors of said trunk circuit by impulses of either direct or alternating current or a combination of both over either or both of said 15 conductors for setting the registers of said sender.

14. In a telephone exchange system an operator's position, a keyset at said position, a 20 trunk circuit and switching mechanism for extending connections from said position, a plurality of register senders common to said trunk circuit for controlling said switching mechanism, means for associating an idle sender with said trunk circuit, two impulsive 25 conductors extending from said keyset to said sender over the connection extending over said trunk circuit, direct current relays in said sender connected through choke coils to each of said conductors, alternating current 30 relays in said sender connected through condensers to each of said conductors, and means controllable by the keys of said keyset for applying direct or alternating current or a combination of both to either or both of said 35 conductors for selectively operating said relays for setting the registers of said sender.

15. In a telephone exchange system an operator's position having a cord circuit, a keyset 40 associable with said cord circuit, a jack ended trunk circuit and switching mechanism for extending connections from said cord circuit, a plurality of register senders common to said trunk circuit for controlling said switching mechanism, means for associating 45 an idle sender with said trunk circuit, two impulsive conductors extending from said keyset to said sender over the connection extending from said cord circuit through said trunk circuit, direct current relays in said sender connected through choke coils to each of said 50 conductors, alternating current relays in said sender connected through condensers to each of said conductors, and means controlled by the keys of said keyset for applying direct or alternating current or a combination of both to either or both of said conductors for selectively operating said relays for setting the registers of said sender.

16. In a telephone exchange system an operator's position having a cord circuit, a keyset 60 associable with said cord circuit, a jack ended trunk circuit and switching mechanism for extending connections from said cord circuit, a plurality of register senders common to said 65 trunk circuit for controlling said

switching mechanism, means for associating an idle sender with said trunk circuit, two impulsive conductors extending from said keyset to said sender over the connection extending from said cord circuit through said trunk circuit, direct current relays in said sender connected through choke coils to each of said conductors, alternating current relays in said sender connected through condensers to each of said conductors, means controlled by the keys of said keyset for applying direct or alternating current or a combination of both to either or both of said conductors for selectively operating said relays for setting the registers of said sender, and means in said trunk circuit controlled by said operator for selectively operating said relays to signal said sender when the operator has completely keyed the desired connection designation. 70 75 80

17. In a telephone exchange system, an operator's position having a cord circuit, a keyset 85 associable with said cord circuit, a jack ended trunk circuit and switching mechanism for extending connections from said cord circuit, a plurality of register senders common to said trunk circuit for controlling said switching mechanism, means for associating an idle sender with said trunk circuit, two impulsive 90 conductors extending from said keyset to said sender over the connection extending from said cord circuit through said trunk circuit, direct current relays in said sender connected through choke coils to each of said conductors, alternating current relays in said sender connected through condensers to each of said conductors, means controlled by the keys of said keyset for applying direct or alternating current or a combination of both to either or both of said conductors for selectively operating said relays for setting the registers of said sender, and means in said trunk circuit controlled by said operator for applying direct current to both of said 95 conductors for operating said direct current relays to signal said sender when the operator has completely keyed the desired connection designation. 100 105 110

18. In a telephone exchange system an operator's position having a cord circuit, a keyset, a key for associating said keyset with said cord circuit, a jack ended trunk circuit and switching mechanism for extending connections from said cord circuit, a plurality of register senders common to said trunk circuit for controlling said switching mechanism, means for associating an idle sender with said trunk circuit, two impulsive 115 conductors extending from said keyset to said sender over the connection extending from said cord circuit through said trunk circuit, direct current relays in said sender connected through choke coils to each of said conductors, alternating current relays in said sender connected through condensers to each of said conductors, means controlled by the 120 125 130

- keys of said keyset for applying direct or alternating current or a combination of both to either or both of said conductors for selectively operating said relays, and means in said trunk circuit operative upon the release of said key for selectively operating said relays to signal said sender when the operator has completely keyed the desired connection designation.
- 10 19. In a telephone exchange system an operator's position, a keyset at said position, a trunk circuit and switching mechanism for extending connections from said position, a plurality of register senders common to said trunk circuit for controlling said switching mechanism, means for associating an idle sender with said trunk circuit, primary and secondary registers in said sender, means controllable from said keyset over two conductors of said trunk circuit by impulses of either direct or alternating current or a combination of both over either or both of said conductors for successively setting the primary registers of said sender, means operative upon the setting of certain of said primary registers for setting said secondary registers therefrom and for then releasing one of said primary registers, and means for then rendering said released primary register again controllable by said keyset controlled means.
- 20 20. In a telephone exchange system an operator's position, a keyset at said position, a trunk circuit and switching mechanism for extending connections from said position, a plurality of register senders common to said trunk circuit for controlling said switching mechanism, means for associating an idle sender with said trunk circuit, primary code and numerical registers and secondary code registers in said sender, means controllable from said keyset over two conductors of said trunk circuit by impulses of either direct or alternating current or a combination of both over either or both of said conductors for successively setting the primary registers of said sender to record the code and numerical digits of desired connection designations, and means operative upon the setting of said primary registers for setting said secondary code registers therefrom, for releasing the first of said primary code registers and for then rendering said first primary code register again controllable from said keyset.
- 25 55. In witness whereof, I hereunto subscribe my name, this 19th day of August, 1931.

CHARLES DE VRIENDT.
